UNITED STATES PATENT OFFICE.

GEORGE CHAMBERLAIN, OF ALLEGHENY, PENNSYLVANIA.

WASHING-MACHINE.

SPECIFICATION forming part of Letters Patent No. 688,593, dated December 10, 1901.

Application filed December 24, 1900. Serial No. 40,910. (No model.)

To all whom it may concern:

Be it known that I, GEORGE CHAMBERLAIN, a citizen of the United States, residing at Allegheny, in the county of Allegheny and State 5 of Pennsylvania, have invented a new and useful Washing-Machine, of which the following is a specification.

This invention relates to washing-machines; and the object is to provide an improved construction of washing-machine by the use of which the clothes may be quickly and effectively cleansed.

With the above object in view the invention consists in the novel features of construction hereinafter fully described, particularly pointed out in the claim, and clearly illustrated in the accompanying drawings, in which—

Figure 1 is a perspective view of a washing-machine constructed in accordance with my invention; Fig. 2, a vertical sectional view of the same; Fig. 3, a bottom plan view, and Fig. 4 is a detail perspective view of the L-shaped guide-bracket.

Referring now more particularly to the accompanying drawings, A designates a rectangular frame supported at three of its corners by legs B, braced by bars C, and having at its other corner a vertical standard D, 30 forming a leg E for that corner of the frame and extending a considerable distance thereabove.

A circular base F of a tub or other receptacle is centrally pivoted to a cross-bar G of the frame and is adapted to rotate thereon, the same engaging friction-rollers H, carried by the frame and disposed at different points thereon. Mounted at its inner end in a bearing-block I, secured to the under side of cross-bar G of the frame, is a shaft J, having its opposite end mounted in standard D and projecting therethrough. This shaft has thereon a friction-disk K, which engages the under side of the circular base F and effects the 40 rotation of said base, which has positioned thereon a circular flange which, together with the base, forms a tub L, as shown. Said friction-disk K may be moved back and forth upon shaft J, so as to vary the speed at which 45 the tub L is rotated, the disk being retained in its adjustment by frictional contact with the shaft. The projecting end of shaft J car-

ries a sprocket-wheel M, around which a chain N passes, said chain passing also around a sprocket O on a driving-shaft P, mounted at 55 one end in the standard D and at its outer end in a bracket Q.

The driving-shaft is provided with a crank-handle R and a driving-wheel S, meshing with a gear T, carried by shaft U, positioned above 60 said driving-wheel, and mounted at its outer end in bracket Q and supported at its inner end by standard D, through which it projects, and on its projecting end provided with a wheel V, having a crank-pin W. 65 The bracket Q is formed of a metal strap secured to the standard D and separated therefrom to support the ends of the shafts before mentioned. This strap is bent to extend over the upper end of said standard and beyond 70 the opposite face thereof, where it is bent downwardly to form an arm X, having its lower end bent at right angles and perforated to form a guide Y for a reciprocable rod, to which the pounder is attached. This is composed of two sections, one of said sections Z being tubular to receive the other section Z', which is adjustable therein and retained in its relative adjustment by set-screw a.

An L-shaped bracket b is secured to the 80 standard, the projecting arm thereof being perforated to form the lower guide for said reciprocable rod, while the vertical portion thereof is slotted to form a guide c for the inner end of an arm d, the outer end of which 85 is secured to the rod of the pounder. A connecting-rod e is pivotally connected at one end with the crank-pin W and at its opposite end to the arm d, so that said pounder-rod is reciprocated as wheel S is rotated through the 90 medium of the driving-wheel.

The lower end of section Z' of the pounder-rod is secured to a plate f, which is substantially triangular in outline, and secured to and depending from the under side of this 95 plate are coiled springs g, the convolutions of said springs being gradually smaller, beginning at their upper ends, so that the springs taper from top to bottom, as illustrated.

Extending upwardly from the frame is an 100 upright h, and connecting this upright with the standard D is a cross-piece i, to which the wringer may be attached.

The operation of the washer will be appar-

ent, the clothes being washed by the action of the plate carrying the springs as the same is reciprocated, the water being forced through the clothes thereby.

5 Having thus fully described my invention, what I claim as new, and desire to secure by Letters Patent, is—

In a washing-machine, a frame, a receptacle rotative on said frame, a shaft carried by the 10 frame provided with an adjustable friction-wheel for engaging the under side of said receptacle, a telescopic rod carrying a pounder at its lower end, a bracket secured to the rear side of the standard, having its upper end 15 bent over said standard and formed into a

bearing for the upper end of said telescopic rod, an L-shaped member, the vertical portion of which is fastened to said standard and has a guideway and the horizontal arm of which has a bearing for said rod, an arm fastened to said rod and guided by said guideway, a wheel having a crank-pin, a rod pivoted to said arm and crank-pin, and mechanism including a hand-crank, on said bracket for simultaneously rotating said wheel and 25 shaft, substantially as described.

GEORGE CHAMBERLAIN.
